their Attorney.

UNITED STATES PATENT OFFICE.

WILLIAM B. KRAKLAU AND CHRIST BRETTSCHEIDER, OF ST. PAUL, MINNESOTA.

AIR-MOISTENING DEVICE.

1,400,444.

Specification of Letters Patent. Patented Dec. 13, 1921.

Application filed April 4, 1921. Serial No. 458,428.

To all whom it may concern:

Be it known that we, WILLIAM B. KRAKLAU and CHRIST BRETTSCHEIDER, citizens of the United States, residing at St. Paul, 5 in the county of Ramsey and State of Minnesota, have invented certain new and useful Improvements in Air-Moistening Devices, of which the following is a specification.

This invention relates to air moistening devices and has for one of its objects to provide readily attachable air humidifying means, for ordinary radiators used in connection with hot water heating plants.

A further object of the invention, is to 15 provide an air moistening device, having automatic mechanism extending into the interior of the radiator whereby a uniform water supply for the device is maintained, whereby the device is rendered self controlling.

A still further object of the invention, is to provide a device of the class described, adapted to be connected to a radiator by means of the usual tapped opening provided 25 to receive the air cock, and the usual central tapped end openings at the top of the radiator, cutting through the end sections thereof. This end opening ordinarily is closed by a removable plug.

30 Another object of the invention is to provide a device of the class described, which will be cheap of construction, efficient in operation and neat in appearance.

To this end the invention consists in the 35 construction, combination and arrangement of parts, hereinafter described and claimed.

In the drawings forming part of this specification.

Figure 1 is a side view of the upper portion of a hot water radiator embodying our 40 invention.

Fig. 2 is an end view of same.

Fig. 3 is a perspective view of the tank of the device.

45 Fig. 4 is a perspective view of the cover for same.

Fig. 5 is a longitudinal section of the supply valve.

Fig. 6 is an enlarged section of the connection between the radiator and the tank, and

Fig. 7 is a transverse section taken on a line cutting the edge of the tank and cover.

A designates a hot water radiator and a 55 an end section thereof. The sections of the radiator shown, are joined together by the usual tapered nipples c, fitting into reamed

seats in the sections, all of the seats being in horizontal alinement so as to form when the nipples are in place a continuous horizontal conduit throughout the length of the 60 radiator, in open communication with the interiors of all of the radiator sections so as to be constantly filled with water under the usual gage pressure of the system. Alined with the nipples c and cutting centrally 65 through the end section a, is the usual relatively large threaded plug opening d. Vertically alined with said plug opening is the tapped air cock opening e.

It is an object of our invention, to utilize 70 said tapped air cock opening, from whence to draw our water supply, and said plug opening through which to extend a pipe into the interior of the radiator, whereby to heat the water in our moistening device. 75

The invention comprises a long rectangular liquid container or tank 1, having a relatively large circular aperture 2 in one of the long walls thereof, and a small opening 3 above said aperture, said aperture and 80 opening registering with the openings d and e of the radiator. Having connection with the tank 1, is the sleeve 4, the latter comprising threaded ends 5 and 6, formed respectively with shoulders 7 and 8, the body 85 portion 9 between said ends being hexagonal in cross section whereby it may be gripped with a wrench. The end 6 of the sleeve extends through the aperture 2 of the tank, and has threaded connection with the nut 90 10, which latter engages the gasket 11 whereby a water tight joint is effected. By firmly setting the sleeve to bring its face 7 into tight relation with the radiator, a water-tight connection is effected between the tank 95 and the radiator. Centrally, the sleeve is tapped to receive the threaded end of the pipe 12, the latter extending through the conduit formed by the nipples c. At its free end, within the radiator, the pipe is 100 closed as by a cap 13 so that the pipe constitutes an extension of the interior of the tank. As the level of the water in the radiator is at all times above the air cock opening 3, the pipe 12 is constantly totally immersed and functions as a heating unit for heating the water in the tank. As the water from the tank completely fills the pipe which latter is level a circulation is set up, causing the water to flow in the direction indicated 105 by the arrows. (Fig. 1.)

Extending through the opening 3 in the

wall of the tank, is the water inlet valve B, having a tubular body 15 formed with a shoulder 16, abutting against the wall of the tank, and having a threaded shank upon 5 which threadedly fits the nut 14, said shank extending through said opening and said nut being screwed against the wall of the tank to force the latter against said shoulder, so as to form a water tight joint between 10 the tank and the water inlet valve.

The valve body 15 is screw-threadedly mounted in the air cock opening e and has a needle valve 16, screw-threaded at its outer free end so that it may be screwed 15 longitudinally of the tubular body. The valve comprises an inner conic portion 17 and an outer oppositely disposed conic portion 18, the valve stem 19 extending beyond the tubular body and being suitably squared 20 at 20, whereby the valve may be adjusted by the use of a suitable key.

The body 15 is formed with seats 21 and 22 adapted to engage respectively with the conic valve portions 17 and 18, so that the 25 valve may be screwed in one direction to shut off the inflow of water from the radiator and in the other to prevent leaking around the stem.

Extending downward at right angles to 30 the bore of the valve body, is the nozzle 23 having a discharge duct 24. The tip of the nozzle is adapted to rest on the rubber disk 25, positioned in the bottom of the cup-like recess 26, in the top of the head 27, which 35 latter may be termed a stopper. Extending from the bottom of the tank is the pivot support 28, carrying the pivot pin 29, whereon is pivoted the float rod 30, the latter carrying at its free end the hollow float 31. 40 The rod 30 rigidly carries the head 27, so as to bring the resilient disk 26 squarely against the end of the nozzle. Obviously, when the tank is full of water, the immersed float will cause the disk to press firmly against 45 the nozzle and thus check the flow from the radiator. Should the water level in the tank fall below a predetermined point, the pressure in the discharge duct will overcome the upward pressure of the float, thereby admitting water to the tank. Thus the water 50 is automatically discharged at the proper time, and thereby a constant level maintained.

A suitable detachable cover 32 is provided, comprising a main angle frame 33 and a secondary frame 34, the two frames frictionally holding between them, in a stretched state, a cloth or wire netting 35, the latter extending over the openings of the frames. 55

Along the lower inner edge of the tank, is 60 the outwardly extending knee 36, extending laterally across the tank, and engaging with the radiator to assist in supporting the tank in vertical position.

What we claim as new:

1. An air moistening device in connection with a hot water radiator, comprising a liquid container, a float controlled water inlet having a discharge opening, opening into the liquid container and in open communication with the interior of the radiator, a pipe in open communication with the interior of the container and extending horizontally into the interior of the radiator, and a shut off valve between said float controlled water inlet and the radiator. 75

2. In an air moistening device, the combination with the upper portion of a hot water radiator, said radiator consisting of vertical sections, each of said sections having a relatively large threaded opening in opposite sides thereof, the openings of all of said sections being in horizontal alignment, nipples threaded into said openings connecting said sections, to form a continuous horizontal conduit, and a relatively small threaded opening vertically above the relatively large threaded opening in the end of section of said radiator; of an air moistening device, comprising a liquid container, a float controlled water inlet threadedly engaging said relatively small threaded opening and having its discharge opening in said container, a tubular extension below said water inlet in open communication with the interior of said container, said tubular extension extending into said conduit, and a plug threaded on said tubular extension at its open end and having water tight connection with the side wall of said container, and threadedly fitting into said relatively large opening in said end section of the radiator. 85 90 95 100

WILLIAM B. KRAKLAU,
CHRIST BRETTSCHEIDER.

Witness:

GEORGE VOELKER.
